UNITED STATES PATENT OFFICE.

ARTHUR J. ARCHAMBAULT, OF CHICAGO, ILLINOIS.

TORCH.

1,260,741.

Specification of Letters Patent. Patented Mar. 26, 1918.

Application filed July 26, 1917. Serial No. 182,826.

To all whom it may concern:

Be it known that I, ARTHUR J. ARCHAMBAULT, a citizen of the United States, residing at Chicago, county of Cook, State of Illinois, have invented a certain new and useful Improvement in Torches, and declare the following to be a full, clear, and exact description of the same, such as will enable others skilled in the art to which it pertains 10 to make and use the same, reference being had to the accompanying drawings, which form a part of this specification.

My invention has for its object to produce a blow torch of simple and rigid construction, adapted to operate efficiently when using as a fuel kerosene or other hydrocarbons heavier than gasoline.

Viewed in its more specific aspects, my invention may be said to have for its objects to produce a blow torch having in a small space a large heating surface adapted to vaporize the fuel before it is discharged from the burner orifice; to produce a vaporizing structure which will be efficiently disposed in the flame of the torch; to produce a vaporizing device which will serve as a shield to prevent the discharge beyond the torch of liquid fuel in case the torch should negligently be placed in a condition permitting 20 a stream of liquid fuel to be discharged through the burner orifice; to produce a torch in which the mixing chamber and a vaporizer of large capacity are formed of a single casting; to produce a torch in which 25 the burner and the supply pipe leading to the burner will be rigidly supported from and braced by the main casting so as to make it practically impossible to damage the torch through rough usage; and to produce 30 a controlling valve in which the needle member may readily be replaced.

The various features of novelty whereby my invention is characterized will herein-after be pointed out with particularity in 45 the claims; but, for a full understanding of my invention and of its objects and advantages, reference may be had to the following detailed description taken in connection with the accompanying drawings, wherein:

50 Figure 1 is a side elevation of a torch

arranged in accordance with a preferred form of my invention;

Fig. 2 is a vertical section through a fuel inlet cap of the torch reservoir;

Fig. 3 is a section taken approximately 55 on line 3—3 of Fig. 1, on a somewhat larger scale;

Fig. 4 is a section taken approximately on line 4—4 of Fig. 3;

Fig. 5 is a section taken approximately 60 on line 5—5 of Fig. 3; and

Fig. 6 is a longitudinal section on a greatly enlarged scale through the end of the burner valve, illustrating the manner of attaching the cleaning needle. 65

Referring to the drawings, 1 represents a reservoir provided with a handle, 2, and an air pump, 3, all of any usual or suitable construction. From the top of the reservoir rises a pipe, 4, from the upper end of which 70 is supported the torch. The torch comprises a combined fuel vaporizer and a device for mixing air with the burning fuel, together with a burner, all of which are of novel and improved construction. The vaporizer and 75 mixer, which I shall call the nozzle, comprises a single casting, 5, in the form of a hollow frustum of a cone, arranged with its axis horizontal as is usual in blow torches. On the under side of the member 5, near the 80 rear or larger end of the latter, is a downwardly projecting boss, 6, which is screwed upon or otherwise attached to the pipe 4. The part 6 is provided with a central passage, 7, which communicates at its upper 85 end with the rear end of one arm, 8, of a V-shaped passage or conduit formed in the wall constituting the under side of the member 5; the passage 8 extending forwardly to a point near the front end of the member 90 5 and there communicating with the front end of the connecting passage 9 which extends rearwardly and, to some degree, upwardly to the rear end of the member 5. In the chamber formed in the member 5 is 95 a V-shaped part, 10, the apex lying a short distance behind the front end of the member 5 and at about the axis thereof and the two arms extending rearwardly; one of the arms being directed downwardly and the 100

other one upwardly as the rear end of the member 5 is approached. The arm which is directed downwardly terminates at the inner end of the passage 9 and is provided 5 with a passage, 11, which communicates at its rear end with the rear end of the passage 9. The other arm of the member 10 is provided with a passages, 12, extending longitudinally through the same, communicating at its front end with the front end of the passage 11, and communicating at its rear end with a burner-supplying pipe, 13, screwed into the rear end of the member 5. It will be seen that the four 10 passages, 8, 9, 11 and 12, constitute a double V or an M with the two apexes displaced so that one lies approximately above the other instead of at the side thereof, so that the fuel which enters through the port or 15 passage 7 has a long way to travel before it reaches the burner-supplying pipe 13.

It is possible to make the member 5 with its tortuous passages in the form of a single casting by making the two V-shaped 20 members solid and then boring the passages into the same from the rear; the rear ends of the passages 8, 9 and 11 being closed by screw plugs, 14 and 15; both of the passages 9 and 11 terminating in the opening closed 25 by the plug 15. Upon removing the plugs, ready access may be had to the interior of the passages for the purpose of cleaning them.

At the rear end of the pipe 13 is supported 30 the fuel injector 16, which is disposed in axial alinement with the member 5; the member 16 being carried upon the end of an arm, 17, projecting laterally from the pipe 13. At the extreme front end of the member 16 is the burner orifice, 18, through 35 which a needle, 19, on the front end of a shut-off valve, 20, is adapted to project. The shut-off valve is provided with a handle, 21, at the rear end of the member 16, and 40 the parts are so arranged that by turning the handle the flow of fuel to the orifice may be permitted or interrupted by the valve 20 and the orifice be kept clean by the movement of the needle back and forth through 45 the same. The whole working part of the needle is smaller than the orifice so that the orifice will not be enlarged through the action of the needle. The orifice 18 is quite small. The cleaning needle, which is preferably about one-thousandth of an inch 50 smaller in diameter than the orifice to prevent it from sticking, must therefore be quite fine and necessarily has to be replaced from time to time. In order to facilitate 55 such replacement, without making it necessary to replace also the shut-off valve, I screw the needle into the end of the shut-off valve as indicated at 22 in Fig. 6. When a new needle is required the old one is sim-

ply unscrewed and a new one put in its place. The orifice, 18, is preferably formed in a little detachable plug, 18^a, so that a new orifice may be provided quickly and easily and without discarding any considerable part of the burner.

The parts 13, 16 and 17 are necessarily comparatively light and in the ordinary torch are often broken or bent accidentally. To avoid accidents of this kind, I have provided the member 16 with two laterally disposed ears, 23, through which extend long screws, 24, whose front ends are screwed into the rear end of the nozzle while the rear ends are rigidly locked to the ears by means of lock nuts, 25, placed between which and the heads of the screws the ears are clamped. The fuel injector 16 is thus supported by three posts consisting of the member 13 and the members 25, distributed around the same and thus forming a rigid, 80 powerful structure. Further stiffening of the parts and protection for the burner is afforded by means of a shield, 26, in the form of a deep cup through the bottom of which the member 16 passes, while the 85 mouth is extended forward into engagement with the rear end of the member 5.

The shield 26 is provided with perforations, 27, for admitting air and the nozzle is provided with perforations, 28, in the 90 body portion thereof and also in the back wall, 29, in the center of which is a large air and fuel opening, 30. The bottom of the chamber in the nozzle is inclined downwardly from the front toward the rear and, 100 in the rear between the bosses into which the plugs 14 and 15 are screwed, namely at the low point of the chamber in the nozzle, is placed an opening, 31, out of which any liquid entering the mixing chamber 105 may flow; such escaping liquid being caught in the usual priming cup, 32, surrounding the pipe 4 below the torch.

The perforations in the body portion and the rear wall of the nozzle serve the double 110 purpose of admitting air to support combustion and of keeping the nozzle cool so that it will not become overheated. Furthermore, particularly when combined with the perforated shield, 26, the nozzle does away 115 with the roaring sound that is made by the flame in all torches with which I am familiar and prevents the torch from being blown out in windy weather.

In the usual torch the chamber in the nozzle 120 decreases uniformly in cross sectional area to the outlet end. I have found that if this construction is employed in my improved torch it will produce a wide flame and, in order to reduce the spread of flame, 125 I have abruptly reduced the outlet end of the chamber in the nozzle. This is conveniently accomplished by providing the outlet end

of the nozzle with an annular inwardly directed flange, 33.

Another feature of my invention has to do with the closing of the fuel inlet into the reservoir. In the ordinary torch the cap 34 is provided with a leather washer which soon ceases to function properly. Instead of a leather washer I employ a washer of lead, as indicated at 35 in Fig. 2.

10 The torch is primed and operated in the usual manner which requires no explanation. It will be seen that as the fuel rises into the torch device it travels through a long passage the walls of which are highly 15 heated, this being particularly true of the two elements of the passage in the V-shaped member 10 which the fuel enters last; the member 10 being wholly enveloped by the flame from the burner and serving as a 20 superheater to carry the vaporization far beyond the point to which it is brought in the passages 8 and 9 which of themselves produce a vaporization of the fuel to as high a degree as the ultimate vaporization 25 obtained in any prior torch of which I am aware. Consequently my improved structure carries the vaporization to a much higher degree than has heretofore been possible, making the torch not only more 30 efficient, but giving a much wider range of control over the flame which may be made to project only an inch or two beyond the torch or be forced outwardly nine inches or more. Where, in the ordinary torch, the 35 burner orifice has a diameter of from six to eight one-thousandths of an inch, my improved vaporizer affords such an increased capacity that I am able to use a burner orifice having a diameter of fourteen one- 40 thousandths of an inch. Another advantage that results from the use of the V-shaped vaporizing conduit within the nozzle chamber is that the torch is not affected to any considerable degree by weather 45 changes for, even if the outer walls of the nozzle become fairly cool in cold weather, the long conduit which is completely enveloped by the flame has sufficient vaporizing capacity to maintain a normal flame.

50 It will also be seen that if for any reason liquid fuel is allowed to squirt out of the burner orifice, it will strike into the crotch of the member 10 so as to be caught in the mixing chamber and flow down into the priming cup instead of shooting out of the front of the torch and thus causing possible damage to surrounding objects.

I claim:

1. In a plumber's torch, a burner, a mixing chamber lying in front of the burner, one of the walls of said chamber having a tortuous fuel passage through the same, and a conduit extending across the interior of the chamber, said conduit being connect-

ed at one end to said passage and at its 65 other end to said burner.

2. In a plumber's torch, a burner, a mixing chamber lying in front of the burner, one of the walls of the chamber having a fuel passage extending therein from a point 70 near the rear end of the chamber toward the front of the chamber and back again to the rear end of the chamber, a conduit extending across the interior of the chamber and connected at one end to one end of 75 said passage, and a connection between the other end of said conduit and said burner.

3. In a plumber's torch, a fuel injector, a mixing chamber lying in front of the fuel injector, one of the walls of the chamber 80 having a fuel passage extending therein from a point near the rear end of the chamber toward the front of the chamber and back again to the rear end of the chamber, and a hollow V-shaped conduit arranged 85 within said chamber with the apex lying at approximately the axis of and in the front end of said chamber and its arms extending rearwardly, the interior of one end of said V-shaped member being connected 90 at one end to said passage and at its other end to said fuel injector.

4. In a plumber's torch, a casting in the form of a hollow frustum of a cone having two converging passages extending longitudinally from the large end toward the small end and joining each other in proximity to the latter end, and having a V-shaped conduit with its apex lying at approximately the axis of said cone and the 100 arms extending to the rear end of the latter, the rear end of the passage in one of said arms joining one of the first mentioned passages in the wall of the casting so as to form a long continuous fuel conduit made up of 105 the four passages.

5. In a plumber's torch, a casting in the form of a hollow frustum of a cone having two converging passages extending longitudinally from the large end toward the 110 small end and joining each other in proximity to the latter end, and having a V-shaped conduit with its apex lying at approximately the axis of said member and the arms extending to the rear end of the latter, the rear end of the passage in one of said 115 arms joining one of the first mentioned passages in the wall of the casting so as to form a long continuous fuel conduit made up of the four passages, a fuel injector connected 120 to one end of said fuel conduit, and means for supplying fuel to the other end of said conduit.

6. In a plumber's torch, a combined vaporizing and air mixing member, a fuel injector lying in rear of said member, a plurality of posts lying in rear of said member around said fuel injector and connect-

ing it and said member together, one of said posts containing a fuel supply passage.

7. In a torch, a nozzle in the form of a hollow frustum of a cone, a burner situated behind the large end of the nozzle, and a fuel supply conduit including a part extending across the interior of the chamber in the nozzle, the nozzle having a narrow

inwardly directed annular flange at the small end thereof for the purpose of producing an outlet smaller in diameter than the adjacent portion of the nozzle chamber. ¹⁰

In testimony whereof, I sign this specification.

ARTHUR J. ARCHAMBAULT.
